UNITED STATES PATENT OFFICE.

FRANK D. POWELL, OF BOSTON, MASSACHUSETTS, ASSIGNOR TO THE LAMSON COMPANY, OF BOSTON, MASSACHUSETTS, A CORPORATION OF NEW JERSEY.

STORE-SERVICE APPARATUS.

1,118,048.

Specification of Letters Patent.

Patented Nov. 24, 1914.

Application filed December 26, 1913. Serial No. 808,740.

To all whom it may concern:

Be it known that I, FRANK D. POWELL, a citizen of the United States, residing at Boston, in the county of Suffolk and State 5 of Massachusetts, have invented certain new and useful Improvements in Store-Service Apparatus, of which the following is a specification.

This invention relates to wire line carriers and more especially to what I have termed up-thrust and down-chute carrier apparatus.

One of the objects of the present invention is to afford provisions in wire line service whereby a carrier may rise over obstructions such as partitions, grilles, etc., or may rise to an upper floor and run at right angles to a station located at a considerable distance from the lower sending point. This type of apparatus will be found particularly useful in serving either up-stairs or basement departments from a central cash desk located either on the floor or upon a balcony. A carrier transmitted over the line wire 25 or track may be powerfully propelled and is hence adapted to operate over lines of great length.

The foregoing and other objects of my invention will be hereinafter referred to 30 and the novel combinations of elements whereby said objects may be attained will be more particularly set forth in the claims appended hereto.

In the drawings which form a part hereof and in which like reference characters designate like parts throughout the several views, I have exemplified a preferred form 35 of the apparatus in question; but as I am aware that various changes and modifications may be made herein without departing from the spirit of my invention, I desire to be limited only by the scope of said claims.

Referring to the drawings: Figure 1 is a 45 side elevation of an elevated cash carrier. Fig. 2 is an end elevation of the same. Fig. 3 is a top view of the elevating apparatus shown to the right in Fig. 1; drawn to a larger scale. Fig. 4 is a detail front elevation of the parts shown in Fig. 3, drawn to a still larger scale for clearness; the car being shown in the act of passing around the curved track. Fig. 5 is a detail end

view of the mechanism shown in Fig. 4. Fig. 6 is a detail perspective view of a portion of the carrier elevating and propelling mechanism. Fig. 7 is a perspective view 55 of the carrier elevating and propelling mechanism. Fig. 8 is a top view of a part of the carrier projecting apparatus shown to the left in Fig. 6. Fig. 9 is a detail section, taken on line IX—IX of Fig. 1. Fig. 10 is a detail section taken on line X—X of Fig. 4. Fig. 11 is a fragmentary perspective rear and back view of a portion of the chaser shown 60 in Fig. 6. Fig. 12 is a detail section taken in Fig. 6. Fig. 13 is a detail section taken on line XII—XII of Fig. 4 and Fig. 14 is a similar section taken on line XIII—XIII of Fig. 4.

The main track or wire 1 extends from a 70 station broadly designated 2 to a curved track section 3; passing together with the latter, and connected thereto in the manner hereinafter described, around a curve of suitable radius, and thence downwardly as 75 at 1' to a plate 4 to which it is secured in any proper manner; the plate 4 being disposed at a considerably lower level than the track 1 and being supported upon uprights 5 or the like. In the present instance 80 the track section 1' is shown as extending through an aperture 6 in a floor 7 intermediate the plate 4 and the track 1. The curved track section 3 preferably consists of a strip of light gage sheet metal 8 which 85 may be stiffened by an additional metal strip 9 of heavier gage but of somewhat less width; both the strips 8 and 9 being in turn riveted to a heavy arcuately curved bar 10, as shown in Fig. 10.

The projecting edge or bead 8' of the strip 8 is curled around the wire 1 and does not materially increase the thickness of the track at this point; it being understood of course that this curled sheet metal edge 95 provides the track surface at this point. It is preferable to file down or otherwise reduce the respective extremities of the curled edge as at 11; to facilitate the passage of the carrier thereover.

The curved track 3 is preferably fastened 100 at its lower extremity to a bar 12 which extends vertically upward and is fastened to a bracket 13; the latter in turn being pivotally or otherwise connected to a hanger 14 105 which may depend from a floor or other suit-

able support. The upper extremity of the curved track may be correspondingly connected to a tie 15 which in turn is preferably pivotally connected, as at 16, to the bracket 13. The tie 15 will be drawn by the tension of the wire track 1 into parallelism therewith and I prefer to unite the extremities of the curved track by a tie-rod 17, to prevent spreading or enlargement of the radius of curvature. Below the hanger and in alignment therewith is a casing 18 the primary purpose of which will be hereinafter referred to, but which secondarily serves to strengthen the frame work of this portion 15 of the projecting mechanism, since the upper extremity of this casing is rigidly connected to the bracket 13 and the lower extremity thereof is connected to a small bracket 18' through which the lower extremity of the tie-rod 17 may extend, as shown in Fig. 4.

Above the wire 1 is a taut wire 19 which may conveniently be bent around an upper surface of the bracket 13 and thence downwardly as at 19' to the plate 4. It will thus be seen that a frame work for the carrier elevating and projecting mechanism is provided; the wires 1' and 19' serving as guides for a slide 20. This slide has pivotally connected thereto a rod 21; preferably square in cross section as indicated in Fig. 6. This rod extends into a spring casing 22 and has a small block 23 mounted upon its upper extremity; which block is adapted to reciprocate in said casing. In the lower extremity of the casing 22 is a guide block 24 which fits the rod 21 and thereby holds the casing 22 against rotation.

Intermediate the blocks 23 and 24 is a short coil spring 25 which serves to break the recoil from the blow delivered by an incoming carrier. Above the block 23 is a similar spring 26 which is placed under compression when a carrier is being propelled outwardly around the curved track section, and which thereby relieves the strain upon the curved track which would tend to deform the same, unless made of unnecessarily heavy material, if the rod 21 were integral with the rod 27 which extends upwardly from the upper end of the casing 22 and which is rigidly connected to the latter. The spring 26 also acts as a bumper spring for incoming carriers. The rod 27 has its upper extremity bent laterally as at 27' (see Figs. 6 and 11); this bent end being journaled in a carriage 28 which carries four small wheels 29. These latter are arranged in pairs and adapted to receive the bead 8' of the curved track 60 snugly therebetween while clearing the remainder of the strip 8 in the same manner as do the wheels of the carrier, hereinafter referred to. For convenience of construction the pairs of wheels 29 may be pivotally mounted upon U-shaped pins 30; the car-

riage 28 being preferably made of sheet metal and having wings 28' upstanding from the body thereof and bent around to house the upper rollers or wheels.

Particular attention is directed to the stop 31 shown in Fig. 11 as extending laterally from one side of the carriage; said stop being adapted to engage the rod 27 when the latter is in substantial parallelism with the track section 1'. The object of this provision is to hold the carriage firmly when the chaser arm, consisting of rods 21 and 27 and the intermediate casing 22, is drawn down so that the car is mounted on said track section 1'. 70 75 30

Forwardly extending from the respective sides of the chaser carriage 28 are resilient metal strips 32 which together with the forward end of said carriage provide a fork which receives a portion of the carriage 33 85 of the carrier, as indicated in Figs. 1 and 4. The direct thrust against the carrier is sustained by a felt buffer 34, or the like.

The slide 20 may be elevated by means of a cord 35 which is connected thereto as at 90 95 and which has therearound a closely coiled wire spring 37; which constitutes a slightly flexible thrust-rod, the lower extremity of which bears against slide 20 and the upper extremity of which normally engages a plunger 38 which is received within the casing 18 above referred to. In this casing is a light coiled spring 36' which is placed under compression when the thrust member 37 is pulled up into the interior of 100 said casing.

The cord 35 emerges from the upper extremity of casing 14, as best shown in Fig. 5, and passes over idlers 39 and down to the pulley block 40. It then passes again 105 upwardly around a pulley 41 and again down to the block 40, around the second pulley therein and finally up to the laterally extending arm 18' of the bracket 13 to which arm it is secured. It is evident, by 110 reason of the tackle thus provided, that in the present instance a downward movement of the pulley block 40 through one foot will elevate the slide 20 four feet. The block 40 is preferably made sufficiently heavy to 115 slightly more than compensate for the weight of the slide 20, the chaser and associated parts, so that normally the upper extremity of the flexible thrust rod 37 will bear lightly against the plunger 38. The 120 latter, it will be noted, is provided with a head which prevents its emergence from the casing 18 so that when the slide 20 is urged downwardly toward plate 4 by the weight and momentum of the incoming carrier, the 125 plunger remains in the position in which it is shown in Fig. 4; it being understood that the weight of the carrier is sufficient to drive the slide 20 down into contact with the buffers 42 which are preferably mounted 130

upon the respective wires 1' and 19'. Buffer springs 43 are provided below said buffers to break the fall of the carrier.

In order that an incoming carrier shall 5 enter the fork of the chaser comparatively free from sidewise oscillatory movement, which it may acquire in transit, I prefer to provide guides 44, which may be light rods bent as indicated in Fig. 3, and supported 10 in yokes 45. These latter may be shaped as 15 shown in Fig. 12; one side being recessed for the reception of the outer side of the curved track and its stiffening elements, which carry the same, and the rods 44 hence 20 being disposed below the level of the track proper, at this point, and upon either side thereof. The station at the upper level may be provided with carrier projecting 25 mechanism of any suitable description; in the present instance said mechanism comprising a hanger 46 which carries a bracket 47 to which the track 1 is pivotally connected by a part 48; the taut wire 19 being similarly connected thereto by a pivotally 30 mounted pulley block 49.

The propelling cord 50 extends upwardly 35 from the handle 51 and is connected to a slidably mounted frame 52 the forward extremity of which is a plate 52', which carries pulleys 53 and a cord 54 which is looped back upon itself over the wire 1, in a known manner, and passes upwardly back and forth around pulleys 54 and those designated 55, which are mounted upon the inner side of a 40 fixed frame 56 which is carried by rods 57 and the wire 19; the extremities of the cord 54 being secured to the plate 52'. This station may be identical in construction 45 with that disclosed in my pending application entitled—Up-send wire line carrier, Serial No. 804,768, filed Dec. 4, 1913, and so need not be herein further described, except to state that when the handle 51 is drawn down the carrier is projected from 50 the position in which it is shown in dotted lines in Fig. 1, toward the downward curve in the track.

The carrier, broadly designated 58, may 55 have the usual spring pressed friction block 59 and wheels 60—61, as described in my said application Serial No. 804,768; said wheels and block being mounted in a frame which is open on one side as at 62 to enable the carrier to ride around the curved track strip 8.

Assuming now that the carrier has been projected from station 2; the operation of the chaser and its associated parts is as follows: The carrier body 33 enters the forked 60 chaser and impinges against the buffer 34 thereof. This drives the chaser carriage back downwardly around the curved track from the position which it normally occupies and in which it is shown in full lines 65 in Fig. 4 and in dotted lines in Fig. 1. The impact of the carrier against the chaser is further taken up by the spring 26 in the casing 22 and the latter together with rod 21, slide 20 and thrust rod 37 move easily 70 downward toward the lower station; the slide bringing up against the buffers 42 and the carrier coming to rest upon track section 1' convenient to the operator at the lower level. While the chaser was thus being driven downwardly, the pulley block 40 75 was raised through a much shorter distance, and the passage of the cord 35 around its pulleys further served to check the momentum of the carrier and insure its delivery at reduced speed at the lower station. 80

The cash box or the like attached to the receptacle is removable therefrom in a known manner and after the operator at the lower station has made the required change or performed some like operation he 85 re-despatches the carrier to the upper station by pulling down upon the cord 63, being aided by the weight of the block 40. This elevates the slide 20 and the chaser arm urges the chaser with the carrier still 90 seated in its fork up track section 1' and onto the curved track; the chaser arm thereafter swinging out of parallelism with track 1' until it reaches the position in which it is shown in Fig. 1. The momentum which 95 the carrier has acquired during its upward movement causes it to leave the fork when the chaser has reached the limit of its upward travel, and by reason of the fact that it was continually and positively propelled 100 during its travel around the curve, it may be caused to travel a long distance over track 1 to station 2, which it enters in a known fashion, retracting the loop of cord 54 and being frictionally brought to rest by the 105 engagement of its block 59 with the usual friction piece or tube 64 on track 1, at said station.

As the carrier passes around the curve, owing to the continued thrust of the chaser 110 therebehind, there is a tendency for the light curved track to be distorted or kinked; but the spring 26 in the chaser arm again comes into action and by yielding relieves the thrust; the energy thus stored in said spring 115 being, however, ultimately delivered, to the carrier just as the chaser comes to rest. The light spring 36' in casing 18 is compressed by the upward thrust of the flexible push-rod 37 as the slide moves from the position 120 in which it is shown in Fig. 4 to that in which it is shown in Fig. 1 or slightly therebeyond, so that said spring is enabled to drive the slide downwardly against the action of the weight 40, when the cord 63 is 125 released, until the head of the block 38 engages the lower extremity of casing 18. This disposes the chaser in position to receive the carrier upon its return from the upper station. The upward movement of 130

the chaser may be limited by the engagement of slide 20 with casing 18, or in any other suitable manner.

Having thus described my invention what I claim is:—

1. A store service apparatus comprising a track having therein a curve, a carrier adapted to travel on said track, and means to thrust said carrier around said curve, said means adapted to follow said carrier around a part at least of said curve and having provisions for reducing the shock of said thrust which is exerted against the curved portion of said track.

15 2. A store service apparatus comprising a track having therein a curve, a carrier adapted to travel on said track, and means to thrust said carrier around said curve, said means adapted to follow said carrier around a part at least of said curve and including a yielding connection for reducing the shock of said thrust which is exerted against the curved portion of said track.

25 3. In store service apparatus, a track having an ascending portion, a curved portion and a portion extending from said curved portion at an angle to said ascending portion, a carrier adapted to travel along said track, a chaser adapted for engagement with said carrier for propelling the latter around the curved portion of the track, a chaser arm, means for elevating the lower end of said arm, the other end of said arm being movable thereby around a part at least of the curved portion of the track, and means for normally returning said chaser and arm to determined positions.

40 4. In store service apparatus, a track having an ascending portion, a curved portion and a portion extending from said curved portion at an angle to said ascending portion, a carrier adapted to travel along said track, a chaser adapted for engagement with said carrier for propelling the latter around the curved portion of the track, a chaser arm, and means for elevating the lower end of said arm, the other end of said arm being movable thereby around a part at least of the curved portion of the track.

45 5. In store service apparatus, a track having an ascending portion, a curved portion and a portion extending from said curved portion at an angle to said ascending portion, a carrier adapted to travel along said track, a chaser adapted for engagement with said carrier for propelling the latter around the curved portion of the track, a chaser arm, and means for elevating the lower end of said arm, the other end of said arm being movable thereby around a part at least of the curved portion of the track, said chaser arm having a yielding connection therein.

60 6. A store service apparatus comprising two stations, a track between said stations

having therein a curve, a carrier adapted to travel along said track, means to propel said carrier from one of said stations around a portion at least of said curve and to thereafter project said carrier along the track to the other of said stations, said means including a chaser which normally remains in contact with the carrier while the latter is traversing at least the greater part of said curve, and means for normally returning said chaser to a determined position.

7. A store service apparatus comprising two stations, a track between said stations having therein a curve, a carrier adapted to travel along said track, means to propel said carrier from one of said stations around a portion at least of said curve and thereafter project said carrier along the track to the other of said stations, said means including a chaser which normally remains in contact with the carrier while the latter is traversing at least a part of said curve, and means for normally returning said chaser to a determined position on said curve preparatory to the reception of the carrier when the latter is re-despatched theretoward.

8. In a store service apparatus, a track having therein a curve, a station at each end of said track, a carrier, and means at each station for projecting said carrier along said track toward the other station, the said means at one station including a chaser adapted to follow said carrier around a portion at least of said curve, said carrier being thereafter movable along said track away from said chaser.

9. In a store service apparatus, a track having therein a curve, a station at each end of said track, a carrier, means at each station for projecting said carrier along said track toward the other station, the said means at one station including a chaser adapted to follow said carrier around a portion at least of said curve, said carrier being thereafter movable along said track away from said chaser, and means for positioning said chaser to receive said carrier when it is projected theretoward by the projecting means at the other station.

10. Store service apparatus comprising a way having a station at one end thereof, a descending portion adjacent said station and a curved portion leading downward to said descending portion, a carrier to travel along said way, and means normally on said curved portion, when said carrier is traveling toward said station, to receive the impact of said carrier and to descend therewith around said curve toward said station.

11. Store service apparatus comprising a way having a station at one end thereof, a descending portion adjacent said station and a curved portion leading downward to said descending portion, a carrier to travel along said way, and means normally on said

curved portion, when said carrier is traveling toward said station, to receive the impact of said carrier and to automatically descend therewith around said curve toward 5 said station.

12. Store service apparatus comprising a way having a station, a carrier on wheels adapted to travel along said way, and a carriage to normally receive said carrier while 10 *en route* toward said station and to travel along therewith to said station, said carriage also having wheels adapted for engagement with said way.

13. Store service apparatus comprising a way having a curve therein, a carriage to 15 travel along a limited extent of said way which includes a portion at least of said curve, a carrier adapted to be propelled by said carriage along said way, and means for 20 propelling said carriage.

14. Store service apparatus comprising a way having a curve therein, a carriage mounted on wheels to travel along a limited extent of said way which includes a portion 25 at least of said curve, a carrier adapted to be propelled by said carriage along said way, and means for propelling said carriage.

15. Store service apparatus comprising a way having a curve therein, a carriage to 30 travel along a limited extent of said way which includes a portion at least of said curve, a carrier adapted to be propelled by said carriage along said way, means for propelling said carriage, and means for retracting 35 said carriage thereafter to a determined position.

16. Wire line store service apparatus comprising a way, having a substantially vertical portion, a laterally extended portion and 40 a curved portion between the portions aforesaid, a carrier to travel along at least said lateral and curved portions of said way, a carriage having attached thereto an arm for thrusting said carriage and thereby said 45 carrier around said curved portion, a slide to travel on said vertical portion, said arm being operatively connected to said slide, and means for elevating said slide.

17. Store service apparatus comprising a 50 carrier, a substantially vertical guide part, a

laterally extended guide part along which said carrier travels, and a curved guide part, a carriage to travel on said curved and substantially vertical guide parts, an arm connected to said carriage and adapted to 55 thrust the latter around said curved part, means to support said arm, movable up and down on said substantially vertical guide part, and means for raising said supporting means and thereby said arm and carriage. 60

18. Store service apparatus comprising a carrier, a substantially vertical guide part, a laterally extended guide part along which said carrier travels, and a curved guide part, a carriage to travel on said curved and substantially vertical guide parts, an arm pivotally connected to said carriage and adapted to thrust the latter around said curved part, means to support said arm, movable up and down on said substantially vertical guide 65 part, and means for raising said supporting means and thereby said arm and carriage. 70

19. A store service apparatus comprising a track having therein a curve and a substantially vertical portion leading up to said 75 curve, a carrier to travel on said track, and means, independent of the carrier, to thrust said carrier up said vertical portion and to continue to thrust it around the greater portion at least of said curve.

20. A store service apparatus comprising a track having therein a curve, a carrier to travel along said track, and means, normally on said curve when said carrier is traveling theretoward to receive said carrier and thereafter travel along therewith.

21. A store service apparatus comprising a track having therein a curve, a carrier to travel along said track, means, normally on said curve, to receive said carrier and thereafter travel along therewith, and guiding means to steady said carrier as it approaches 90 said receiving means.

In testimony whereof I have affixed my signature, in the presence of two witnesses. 95
